ROBERT C. LINTON, OF MAPLEWOOD, MISSOURI

MAKE-UP DEVICE FOR PRINTING FORMS

Application filed June 24, 1929. Serial No. 373,121.

This invention relates generally to make-up devices for printing forms, and more particularly to an improved device adapted to provide space in a printing form for cuts, the predominant object of the invention being to provide improved means of this type comprised of separable parts which may be quickly and easily assembled and dissembled in use.

10 In making up printing forms intended for use particularly in printing newspapers it frequently happens that a cut, which is to form part of a printing form, is not available at the time the form is being made up, and when this situation arose prior to this invention it was necessary that a piece of material be cut to the size of the unavailable cut, and this piece of material was arranged in the form in the position of the cut so as to 15 maintain a space in the cut of the size and shape of the cut. With the piece of material referred to arranged in the form in the position of the cut, the type of the form was arranged about the position of the cut, and 20 when the cut was received the piece of material was removed from the form and the cut substituted therefor.

Due to the fact that much time was consumed in cutting and preparing the piece of 25 material which heretofore provided the space for the cut, I have provided the device disclosed herein, which, briefly stated, comprises a plurality of elements provided with slots adapted to receive the end portions of bars. 30 The slotted elements are so constructed that said elements and the bars associated therewith may be assembled to provide structures of various shapes and dimensions, hence structures provided by assembling said parts 35 may be employed to provide spaces in printing forms for cuts of a great variety of shapes and sizes.

Fig. 1 is a perspective of one of the slotted 40 elements of my improved make-up device.

Fig. 2 is a plan view of my device in an assembled condition as same will appear when arranged to provide a rectangular space in a printing form.

Fig. 3 is a view similar to Fig. 2, but show-

ing the device as same will appear when arranged in triangular formation.

Fig. 4 illustrates a modified form of the invention.

Fig. 5 is a perspective showing a quad provided with slots so that same may be used as a part of the invention. 55

In the drawings, wherein is shown for the purpose of illustration, merely, one embodiment of the invention, A designates my improved make-up device, which comprises a plurality of elements 3 and bars C, which are extended between certain of said elements to provide the make-up structure. In the preferred construction of the elements B, same 60 are in circular form and of solid construction, and each thereof is provided with a plurality of radial slots 1, some of which are longer than others thereof.

The opposite end portions of the bars C are 70 extended into certain of the radial slots 1 of the elements B in a manner to join said elements together, and said bars C extend between said elements in the manner indicated in Figs. 2 and 3. If desired, I may taper 75 the slots 1 very slightly from top to bottom with the wider portion of the slots located at the top of the elements B, and in this event the bars C, or at least the opposite end portions thereof, will be correspondingly tapered. This arrangement will assure free 80 passage of the end portions of the bars into the slots and close contact between the side faces of the bars and the walls of the slots, whereby a very rigid structure will be provided. Arranged to surround the structure 85 comprised of the elements B and bars C are bars D, which provide the built-up structure with flat marginal walls, said bars being arranged in contact with the peripheral faces 90 of the elements B, as shown in Figs. 2 and 3.

In the use of my improved device, a plurality of the elements B is arranged in the relative positions necessary to provide a make-up device of the desired configuration, 95 and said elements are joined together by bars C, the opposite end portions of which are introduced into certain of the radial slots of said elements. Due to the fact that the radial slots are quite numerous, and because 100

said slots extend entirely around the elements B, the bars C may be extended in a great variety of angles, hence the make-up device may be caused to assume a very great number of shapes. Also, inasmuch as the bars C may be of various lengths, the dimensions of the make-up device may vary as desired. After the elements B and the bars C are assembled as described, the marginal bars D are arranged in contact with the peripheral faces of said elements to provide the make-up device with flat marginal walls.

When the make-up device has been assembled and is in place in the form, said form is completed by arranging the type of the form in place about the make-up device. The form having been completed except for the presence of the cut therein, and the cut now being available, the make-up device A is removed from the form either by lifting the same out as a unit, or by disassembling the various parts of which said make-up device is comprised and removing said device piece by piece, after which the cut is arranged in the space in the form provided therefor by the make-up device A and the form is locked up and is ready for use.

In Fig. 4 I illustrate a form of the invention in accordance with which the inner ends of the slots 1' of the elements B' are provided with slightly enlarged circular portions 2. Also in this form of the invention the bars C' are provided at the ends thereof with enlarged circular portions 3 which enter the circular portions of the slots 1' when the end portions of the bars C' are introduced into the slots 1'. The bars C' are also provided with shoulders 4, which contact with the peripheral faces of the elements B' when the end portions of the bars C' are extended into the slots 1'. The circular portions of the slots 1' and the bars C' and the shoulders 4 contacting with the peripheral faces of the elements 1' serve to securely lock the elements B' and bars C' together, which condition is highly desirable in some types of printing form building.

In Fig. 5 I illustrate the manner of preparing a quad for use as a part of my device, said quad 5 being provided with slots 6, which are adapted to receive the end portions of the bars C (not shown in Fig. 5) in the same manner that the slots 1 of the elements B of the preferred construction of the invention receive said bars. When constructed as shown in Fig. 5, the quads may, in certain types of work, be used in place of the elements B and B'.

I claim:

1. A make-up device for printing forms comprising a plurality of elements having a plurality of radially formed slots formed in each thereof, and bars for joining said elements together, the end portions of said bars being extended into certain of the slots

formed in said elements and said bars being separable from said elements.

2. A make-up device for printing forms comprising a plurality of elements having a plurality of radially formed slots of varying lengths formed in each thereof, and bars for joining said elements together, the end portions of said bars being extended into certain of the slots formed in said elements and said bars being separable from said elements. 75

3. A make-up device for printing forms comprising a plurality of elements having a plurality of slots formed in each thereof, bars for joining said elements together, the end portions of said bars being extended into certain of the slots formed in said elements, and marginal bars surrounding the assembled elements and bars for providing the device with flat marginal walls. 80

4. A make-up device for printing forms comprising a plurality of elements having a plurality of slots formed in each thereof, bars for joining said elements together, the end portions of said bars being extended into certain of the slots formed in said elements, and marginal bars surrounding the assembled elements and bars for providing the device with flat marginal walls, said marginal bars being arranged in contact with faces of said elements. 85

In testimony that I claim the foregoing I hereunto affix my signature.

ROBERT C. LINTON.
